UNITED STATES PATENT OFFICE.

JOHN F. ROBB, OF CLEVELAND HEIGHTS, OHIO, ASSIGNEE TO KOEHRING COMPANY, OF MILWAUKEE, WISCONSIN, A CORPORATION.

CEMENT LOADING, CONTROLLING, MEASURING, AND COUNTING APPARATUS FOR CONCRETE MIXERS.

Application filed May 6, 1926. Serial No. 107,237.

- Concrete mixing machines today are used in various ways, on building construction, pavement or road construction, and in practically all concrete engineering operations. 5
- 5 The operation of these machines requires close inspection for ensuring the integrity of the ultimate product. For instance, the time of mixing is controlled, the proportioning of aggregates closely supervised, the 10 amount of water in each batch handled is varied as necessary and for best results depending on moisture and sand, etc., and the cement used carefully measured manually by counting of bags for each batch mixed. 15
- 15 On certain municipal, State and Federal Government controlled jobs, inspectors are employed to see to accurate measuring of cement, and otherwise closely supervise mixing operations. 20
- 20 By my invention, inspection is done away with, or minimized to a negligible degree, by mechanically measuring and registering the cement control, and also mechanically controlling the cement and water ratio of 25 batches of aggregates handled by the mixer. The measurement is positive, accurate, and the registration results are or may be under lock and key. Once machine is set and adjustment noted by the inspector, the inspection 30 may be made periodically at leisure. The contractor is advantaged by having automatic control of cement, and cement and water, and by having complete registration of all work and cement handled by his mixing machine. 35
- For a full comprehension of this invention, I shall briefly refer to certain practise in use today in handling concrete aggregates for mixing and laying down, as pavement. 40
- 40 Machines of the type employed for the above purpose are ordinarily known as concrete mixing pavers and generally are of the type disclosed by such patents as that of E. H. Lichtenberg, #1,141,470, issued June 1st, 1915, and J. F. Robb, #1,370,407, issued March 1st, 1921, and embody a portable traction support carrying a concrete mixer, a loading skip for hoisting solid aggregates of cement, sand and stone to charge the same into the mixer, and a boom and bucket or other distributor by which the said aggregates mixed with water, are placed upon the sub-grade to make the pavement. 50
- This invention deals primarily with the handling of the cement and water which 55 form parts of the aggregates that provide the ultimate concrete. Moreover, the invention is not limited in its usefulness to portable type machines for concrete mixing purposes, but is equally adapted for use in connection with stationary concrete mixers such as may be operated in a central mixing plant from which the concrete in mixed condition will be taken off to the site where it is to be used. The place of use may be a sub-grade where a pavement is being laid or it may be a building or some concrete work that is being constructed. 60
- Now it has heretofore been the practise to measure the cement forming a part of 70 the concrete aggregates largely by manual labor. Thus in larger jobs, two or more men will be employed to open the bags of cement, each of which contains a cubic foot of the material, and either discharge these 75 bags in a motor vehicle which is to carry the aggregates to the mixer, as in paving operations, or the cement is deposited by the men in a loading skip direct, in wheelbarrows, or in any receptacle, that will enable it to be 80 conveniently combined with the sand and stone. When the cement, sand and stone are together they are dumped into the mixer by suitable charging means, usually a loading skip and simultaneously they are supplied 85 with the proper proportion of water to give the proper mixture. 90
- The most important ingredient of a batch of concrete is the cement and several bags or cubic feet is the customary charge 95 for mixers of any size. A convenient means of counting these bags is greatly to be desired for determining the ultimate integrity of the mix and to generally facilitate keeping tab on the amount of cement used upon a job. The measuring and conveying machine of this invention is designed to meet the above noted requirement and comprises a loading or conveying device that will 100 count the number of bags or cubic feet of cement that are combined with each batch of aggregates that are handled by the mixer. A feature of primary importance of my present invention is the combining with the mixing machine itself of the cement conveying or measuring feature or mechanism, and the interlocking of the controls by 105 which the cement measuring means acts

along with the charging device or skip and the water supply means.

In connection with the water supply means as used with my cement measuring machine, another feature of primary importance of the invention is involved. It is generally accepted today that if the cement and water ingredients of a concrete batch are controlled in proper proportions, the remainder of the batch comprising sand and stone may be combined in suitable proportions to make a workable batch without fear of the ultimate concrete being of defective construction. In line with this accepted theory and practise, that is being put into use considerably today I associate my cement measuring means with the water supply means in a peculiar way so that the supply of water is directly proportioned to the amount of cement which is fed to the mixing machine. So far as I am advised, it is entirely new to employ a cement measuring device that mechanically handles the cement which may be manually fed or otherwise supplied thereto in conjunction with a concrete mixer; also with water supply means, and therefore I desire the claims to these features to be interpreted in the light of this novel phase of the invention.

In addition to the foregoing my invention contemplates certain novel mechanisms for supplying cement to my measuring and loading device that works in conjunction with the mixing machine, together with a novel association of the measuring device for the loading skip means of the machine, or any equivalent means, establishing control phases of operation between the two.

With the foregoing in view, I note that my invention comprehends the employment of a cement measuring means consisting preferably of a bucket type loader, the buckets of which are adapted each to receive the contents of a bag of cement, the loader being mounted upon the support for the mixing machine, being automatically operable under the influence of the loading or discharging skip, and being automatically stopped when the cement hopper that supplies the skip or mixing machine is filled. With the cement hopper may be associated the water receptacle or tank operated automatically incident to the filling and discharging of said hopper for purposes previously outlined. A batchmeter such as ordinarily employed for mixing machines is availed of and is used to coact with certain features of the water supply mechanism.

Referring to the drawings of my invention, I briefly describe the figures as follows:

Figure 1 is a concrete mixing paving machine of the portable type illustrating my invention adapted thereto, my mechanism proportioning the amount of loose cement

delivered to the loading skip before combining with the sand and stone therein.

Figure 2 is a somewhat diagrammatic front elevational view showing the skip in grade position and the delivery spout positioned over the skip for delivery of cement thereinto.

Figure 3 is an elevation of the trip hopper assembly shown somewhat diagrammatically.

Figure 4 is a vertical sectional view through one of the receptacles of the triple hopper and the discharge hopper for the conveyer showing the cooperation of the doors with the hopper's edge.

Figure 5 is a fragmentary enlarged elevation of the upper portion of the conveyer and the clutch control instrumentalities therefor.

Figure 6 is a sectional view through the conveyer supporting frame and one of the buckets showing more clearly the weighing mechanism therefor.

Figure 7 is a detailed perspective view of a portion of one of the U-shaped supporting members and one of the weight determining springs.

Figure 8 is a vertical sectional view through the bag counting and control mechanism.

Figure 9 is an enlarged fragmentary sectional view taken at right angles to Figure 8 showing more clearly the instrumentalities for returning the counting disc to starting position.

Figure 10 is a fragmentary detail perspective view showing the actuating means for swinging the spout.

Figure 11 is a detailed view of the end portion of the spout showing its door and the cooperation of the opening lever therefor with the side of the skip.

Figure 12 is a somewhat diagrammatic rear view of the upper portion of a concrete mixing machine embodying my cement measuring loader and showing a modification of the invention wherein the water supply of the machine is controlled efficiently to properly proportion the amount of cement and water used for a particular batch, the same being done automatically.

Mixing machine.

Referring to the drawings, I designate the frame of the concrete mixing machine illustrated as 1. The said frame 1 supports the concrete mixer 2 and the boom and bucket distributing attachment therefor is generally designated as 3 and 3'. For charging the mixer 2 with concrete aggregates, I employ the usual skip 4. The machine is equipped with a batchmeter 5 for its known purpose of controlling the period of mixing of the aggregates charged into the mixer 2 by an audible signal and by unlocking of

the discharge chute of the mixer, and if necessary by actually operating said chute somewhat after the manner indicated in the Robb chute patent previously identified. 5 The skip 4 will be hoisted by the usual hoisting cable means 5' and said skip is pivoted to the frame 1 at 6 by means of a supporting bracket or arm 7 attached to said skip.

10 *Cement supply means.*

Suitably mounted at the end of the machine near the boom and bucket attachment 3-3^a is a platform 8 on which the man who feeds the cement to the measuring device 15 may stand and which platform may also be used to receive and support a number of bags of cement or they may be loaded directly onto the platform 8 from a motor vehicle bringing them up from the supply 20 point to the mixing machine, or if desired as indicated in Figure 2, the bags of cement may be conveyed to the platform 8 by an endless conveyer 10 that leads laterally from the mixing machine frame 1 a suitable distance. 25 This distance may be to the side of the road if the machine is laying pavement, or to a cement supply compartment if the mechanism is in a central mixing plant. Or the bags may be skidded down an inclined 30 chute in a central mixing plant to supply the operator at the platform 8.

Cement measuring device.

From the platform 8 the cement feeder 35 or feeders, one or two men, will feed the cement into a movable supply hopper 11, see Figure 3, adapted to shift transversely of the supporting frame work 1 of the machine and comprising three compartments A, B 40 and C. This supply hopper 11 is really supported on rollers or wheels 12 traveling on tracks 13 arranged transversely of the machine and while it may be moved by hand, it is shown as automatically operated in the use 45 of the machine, the automatic actuating means to be described later on. At this point it suffices to state that the hopper 12 is movable above a cement feed hopper 14 so that each compartment A, B or C may 50 supply its contents to the hopper 14.

From the hopper 14 which is of sufficient size to hold preferably a cubic foot or bag of cement only, the cement is adapted to be supplied by opening of the bottom door 14^a of the hopper, to my measuring device which consists of an endless bucket loader mounted upon a suitable supporting frame 15 projecting from one side of the frame work 1 of the machine. The endless bucket loader 60 comprises an endless belt or chain device 16 which inclines upwardly from the boom and bucket attachment end of the machine to a point adjacent to the upper diagonally opposite portion of the frame 1. The endless 65 conveyer belt or chain 16 will be equipped

with a number of loading buckets 17, each bucket having the capacity to receive at least one cubic foot of cement from the hopper 14. The buckets are seen best in Figures 5 and 6 as being yieldably mounted upon the conveyer belt 16 by means of spring supports 18, the detail construction of which is shown in Figures 5, 6 and 7.

It suffices to state that when the buckets 17 are empty, the springs of the spring supports 18 hold the empty buckets slightly upraised as in the dotted line positions in Figures 5 and 6. When a bucket 17 has been filled with its measured quantity of cement, the weight of the cement causes the bucket 80 to lower to its full line position of Figure 5. This action is somewhat important because projecting from a side of the buckets is an arm 19 which is arranged to operate in a path of movement enabling it to strike a 85 trip lever 20 near the upper end of the loader or conveyer, when the bucket 17 carrying said arm is weighted down by the contents thereof. If the bucket is empty the arm 19 passes freely by the trip lever 20 so as not 90 to actuate the latter. The trip lever 20 is designed to operate certain registering mechanism which counts the number of bags of cement that are handled by the loader and therefore handled by the whole mixing machine and also counts the number of batches of cement handled. By batch of cement I mean the number of bags which frequently varies dependent upon the size of the mixer, which is necessary to be combined with a proportionate batch of sand and stone and water. By counting the batches of the cement, the number of batches 100 of aggregates handled by the machine will be registered for obvious reasons and it is 105 desirable to maintain a notation thereof.

The reason for the action of the buckets 17 as described is to prevent the buckets from operating the registering means when the buckets are not loaded or filled with a 110 bag or cubic foot of cement. Referring to Figure 5, it will be seen that the trip lever 20 is pivoted at 21 and its axis carries an arm 22 attached to a rod 23 extending to a lever 24 supported on the case 25 in which 115 certain of the counting mechanism is located. The lever 24 carries a pawl 26 arranged to engage a ratchet operating disc 27 equipped with a series of pin or stud receiving openings 28. A trip pin 29 is adapted to be adjusted so as to be received by a selected one of the openings 28, its position being controlled by the number of bags of cement which are to make up a batch thereof for a batch of concrete. Associated with the openings 28 are numbers running consecutively 120 and carried by the disk 27, each number being visible at a sight opening 30 in the casing 25. Cooperative with the disc 27 is a detent pawl 31 to temporarily detain the 125

- disc 27 after it has been moved one increment of its registering movement. Also cooperative with the disc 27 is a helical return spring 32 to restore the disc to a zero position. The detent pawl 31 holds the disc 27 in the position to which it is advanced by the action of the operating pawl 26 until in the rising movement of the loading skip 4 at a certain point in said movement of the loading skip 4, the skip will trip upwards a bar 33, see Figure 1, by means of a pin 34 on the bracket 7. This upward movement of the bar 33 is sufficient to rock a bell crank lever 35 on the upper portion of the frame 10 work 1 and impart movement to an actuating rod 36 that rocks the lever 37, (see Figures 1 to 8), thereby raising the detent pawl 31 and releasing the disc 27 to permit it to zeroize.
- 20 The operating pin 29 carried by the disc 27 is in the sixth bag position in Figure 8. By this is meant that when six of the buckets 17, filled with cement, have been elevated by the conveyer 16 so as to trip the lever 20 25 and dump into the hopper 38 six bags of cement, equivalent to six cubic feet, a clutch throwout lever 39, see Figure 8, in the casing 25, will have been struck by the pin 29 and rocked downwards to thereby rock the arm 30 40 which, as best seen in Figure 1, leads downwardly from the register casing 25 to a bell crank lever 41 having connection with the clutch throwout lever 42 by means of a rod or bar 43, see Figure 5.
- 35 The clutch throwout lever 42 is adapted to operate a clutch yoke 44 that shifts the operating clutch for establishing a driving connection from the power means of the mixer, to the cement loader or measuring device.
- 40 The clutch aforesaid is carried by a shaft 45, see Figure 1, and said shaft 45 is adapted to drive a sprocket chain 46 which connects the shaft 45 to a shaft 47 at the lower end of the conveyer 16. As the details of the 45 clutch means are unimportant to the invention the same are only conventionally illustrated and referred to.
- 50 It will thus be seen that by the action of the measuring device or loader when a predetermined batch of cement has been dumped into the hopper 38, the number of bags in the batch will have been registered at the sight opening of the register casing 25, and an audible signal 48, see Figure 8, 55 will have been sounded by the action of a tappet 49 with which the knockout lever 39 contacts by means of a hook 50, and the feeding of cement into the hopper 38 will have been discontinued by a throwing out of the 60 clutch acted on by the clutch yoke 44. Moreover, at this time, a batch of cement will have been registered on the batch register 25^a which is located beneath the bag counting register 25 previously described.
- 65 The register 25^a is actuated by the down-

ward movement of the rod 40^a which connects the arm 40 with the lever 41 of the clutch throwout actuating connecting means.

Skip control from measuring device.

It is notable that as a part of the general mechanism of my mixing machine, I use a control lever 51, see Figure 5, by which the operation of raising the skip 4 through the cable means 5 is controlled. The said lever 51 is prevented from operating to raise the skip until after the movement of the conveyer 16 and its buckets 17 have stopped. The interlock for this purpose is found in Figure 4 as comprising a locking catch 52 on a rock shaft 53 that has an arm 54 beneath one arm of the bell crank 41. Thus when the clutch lever 42 is operated to throw out the clutch means and stop the movement of the conveyer the rock shaft 53 will be simultaneously operated to raise the catch member 52, release the lever 51 and permit the skip 4 to be hoisted.

Discharge of measured cement.

The cement batch hopper 38 has, according to the foregoing description been filled with a batch of cement of proper proportion to be mixed with sand and stone in the skip 4. The said batch of cement is retained in the hopper 38 by means of a bottom closing door 55 near the lower end of said hopper, said door adapted to rock downwardly to open or discharge the hopper. Normally while the skip 4 is in its lowered position, as seen in Figure 1, the pivot bracket 7 of the skip rests upon the horizontal arm 56 of a vertical actuating rod 57 normally impelled to rise in its bearing in a bracket arm 58 by means of a spring 59, see Figure 1. The rod 57 is connected by an arm with the pivotal axis of the door 55 and as the skip 4 is started in its upward movement it will be apparent that the rod 57 will move upwards by the action of the spring 59 and open the door 55. The charge of cement in the hopper 38 will thus pass by gravitating movement into a spout 60 that is pivoted for movement about the vertical axis 61 and communicated with the lower end of the hopper 38. The spout 60 may or may not be used, and I say this because the hopper 38 may be arranged to discharge directly into the skip 4 as is shown in Figure 12, or it may be arranged to discharge into the stationary charging chute 62 that feeds the concrete aggregates into the mixer 2. The particular arrangement is not material to the invention but as shown in Figure 2 and Figure 1, I do avail of a movable spout 60 to carry the aggregates following from the hopper 38 over and into the skip 4. As the discharge of the contents of the hopper 38 into the skip 4 through the spout 60 is done comparatively quickly, it will be evident dur-

ing the initial rising movement of the skip 4 after the cement is supplied thereto I may arrange for movement of the spout 60 from its position above the skip. To this end, I provide on the lower end of the pin or axis 61 of the spout 60, a lateral arm 63 engageable by a cam 64 on the bracket 7 or the skip, see Figure 10. As the skip starts to rise under the lifting action of the cables 5', the cam 64 escapes from the arm 63 and a coiled spring 65 encircling the axis member 61 causes the latter to turn and thereby carry the spout from the path of movement of the skip. On return downward movement of the skip, this same arm 63 is struck by the cam 64 and the spout is turned into the position from which it will discharge into the skip from above the same. Of course at the time the cement passes 20 into the skip 4 from the spout 60 or from the hopper 38 directly, the sand and the stone will already have been received by the skip being placed therein from the motor vehicle or otherwise deposited according to 25 whether my machine is used out on a paving job or at a central mixing plant. I have previously described how as the skip moves upwards the rod 33 is actuated to release the register and operating disc 27 and restore 30 the same to zero through the action of the rod 36, lever 37 and detent pawl 31. The pin 34 which raises the rod 33 will escape from the shoulder 33^a of the rod by the action of a cam 33^b engaging the abutment projection 33^c on one of the diagonal struts of the frame 1.

Reverting now to the operation of feeding the cement from the feed hopper 14 into each bucket 17 as it passes beneath said hopper, I note that the bottom door 14^a of the hopper 14 has an extension 14^b in the path of movement of the upper portion of each bucket 17. Likewise this bottom door 14^a has a side wing which is notched to receive 45 a projection on a trip lever 66, the extensions from a side of the hopper 14 into the path of the pin 19 off-standing from the lower end of each bucket. Assuming that the hopper 14 is filled with a cubic foot or bag of cement therefore as each bucket passes upwardly with the conveyer 16 its pin trips the lever 66, releases the door 14^a and the door gravitates and deposits the measured quantity of cement in the bucket next beneath. After the cement has gravitated into such bucket, the same bucket by abutting with the door 14^a raises the door again until it is latched by the latch lever 66 which has at this time escaped from the pin 19 of the next uppermost bucket and this action is continuous while the conveyer 16 is in operation.

Triple supply hopper.

55 I have shown in Figure 3 some mechanism

which I may or may not use as desired for the automatic movement of the triple supply hopper 11. Thus it will be noted that I use a Geneva movement 69 which is driven by bevel gearing 70 on the lower sprocket 70 and operating shaft of the conveyer 16, see Figure 2, as well as Figure 3. In the operation of the Geneva movement 69, the arm 71 of the latter is caused to revolve, making a quarter revolution on each intermittent 75 movement. The said arm 71 is connected by a rod 72 with an operating lever 73 that is attached by a link 74 to an arm 75 secured to a side of the supply hopper 11 as the triple hopper 11 is moved to the left to discharge the receptacle C, the pin 76 on the feed hopper 14 will strike the door tripping lever 77 and through the toggle links 77^a and 77^b will cause both doors 78 at the bottom of the receptacle C to be opened dumping the 80 contents thereof into the feeding hopper 14. The releasing mechanism aforesaid is duplicated on the receptacle or compartment A of the hopper 11 with the exception that the release of the doors of this compartment A is effected incident to the movement of the triple hopper 11 at the right, whereas the release of the doors of the receptacle C was performed incident of the receptacle C to the left. The doors 78 are self 85 closing by reason of the cooperation of their bottom cams with the edges or sides of the hopper 14, and during the movement of the particular empty compartment or receptacle from its position above the feeding hopper 14. With the trip hopper 11 in the position shown in Figure 3, as the arm 71 moves through a quarter of its arc of movement the trip hopper 11 will be moved to position the central compartment B above the feeding hopper 14. The trip pin 76 will strike the release lever 77^a moving the same to the left and unlatching the latch mechanism 79, thereupon the spring 80 will cause the doors of the compartment B to swing downwardly 90 and dump the contents of the compartment into the hopper 14. With the trip hopper 11 in the position shown in Figure 3, as the arm 71 moves through a quarter of its arc of movement the trip hopper 11 will be moved to position the central compartment B above the feeding hopper 14. The trip pin 76 will strike the release lever 77^a moving the same to the left and unlatching the latch mechanism 79, thereupon the spring 80 will cause the doors of the compartment B to swing downwardly 95 and dump the contents of the compartment into the hopper 14. With the trip hopper 11 in the position shown in Figure 3, as the arm 71 moves through a quarter of its arc of movement the trip hopper 11 will be moved to position the central compartment B above the feeding hopper 14. The trip pin 76 will strike the release lever 77^a moving the same to the left and unlatching the latch mechanism 79, thereupon the spring 80 will cause the doors of the compartment B to swing downwardly 100 and dump the contents of the compartment into the hopper 14. With the trip hopper 11 in the position shown in Figure 3, as the arm 71 moves through a quarter of its arc of movement the trip hopper 11 will be moved to position the central compartment B above the feeding hopper 14. The trip pin 76 will strike the release lever 77^a moving the same to the left and unlatching the latch mechanism 79, thereupon the spring 80 will cause the doors of the compartment B to swing downwardly 105 and dump the contents of the compartment into the hopper 14. With the trip hopper 11 in the position shown in Figure 3, as the arm 71 moves through a quarter of its arc of movement the trip hopper 11 will be moved to position the central compartment B above the feeding hopper 14. The trip pin 76 will strike the release lever 77^a moving the same to the left and unlatching the latch mechanism 79, thereupon the spring 80 will cause the doors of the compartment B to swing downwardly 110 and dump the contents of the compartment into the hopper 14. With the trip hopper 11 in the position shown in Figure 3, as the arm 71 moves through a quarter of its arc of movement the trip hopper 11 will be moved to position the central compartment B above the feeding hopper 14. The trip pin 76 will strike the release lever 77^a moving the same to the left and unlatching the latch mechanism 79, thereupon the spring 80 will cause the doors of the compartment B to swing downwardly 115 and dump the contents of the compartment into the hopper 14. With the trip hopper 11 in the position shown in Figure 3, as the arm 71 moves through a quarter of its arc of movement the trip hopper 11 will be moved to position the central compartment B above the feeding hopper 14. The trip pin 76 will strike the release lever 77^a moving the same to the left and unlatching the latch mechanism 79, thereupon the spring 80 will cause the doors of the compartment B to swing downwardly 120 and dump the contents of the compartment into the hopper 14. The men who do the feeding work will cut the strings of the bags of cement just before dumping them into the triple hopper 11.

General operation of machine.

Assuming that the cement hopper 38 is filled with a batch of cement, and the skip 4 is upraised and is moving downward to its 130

sub-grade position, at a predetermined time in the downward movement of the skip, the rod 57 will be operated to open the door 55, the spout 60 leading from the hopper 38 having been previously actuated by the skip bracket 7 through the arm 10, to assume a position above said skip. In this way, the cement is dumped into the skip 4 and the latter may receive the sand and stone aggregates in the usual way. The skip operating lever 51 is in released condition as respects the latch 52, because at this time, while the skip is down, the conveyer 16 is stopped.

The skip 4 may then be raised by actuating the lever 51 and as the skip rises the rod or bar 33 is operated to set the conveyer 16 into motion, through the release and restoration of the registering and operating disc 27 from the detaining action of the pawl 31. The restoration of the disc 27 releases the clutch operating lever 39 and permits a spring 39^a attached to said lever to move the same in such a manner as to throw in the clutch of the conveyer 16 by downward actuation of the rod 40^a previously described. As the skip 4 rises, the door 55 of the hopper is of course closed by the spring 59 and the spring 65 shifts the spout 60 out of the path of the skip in its upward movement. The conveyer 16 now being in operation and its buckets 17 properly supplied with cement from the hopper 14, the conveyer will move until, according to the adjustment of the pin 29 in Figure 8, six full buckets of cement are dumped into the hopper 38. At such time, the controlling and registering disc 27 will have been operated to move the pin 29 to rock the lever 39 and throw out the clutch which carries the drive from the engine to the conveyer 16, through actuation of the clutch lever 42, see Figure 5. Thereupon the conveyer 16 will be stopped and a batch of cement will be ready in the hopper 38 to be discharged therefrom through the spout 60 into the skip 4, on the next downward movement of the skip.

In the above operation the register 25 may be observed to note the number of bags of cement indicated as comprising the batch, and the register 25^a will permanently record the complete batch as having been dumped into the hopper 38.

Cement and water measuring control.

I now pass to the construction of my invention as embodied in Figure 12 which affords certain simplification of mechanism over that as presented in the other figures of the drawings. I again refer to the fact that according to scientific exhaustive tests, it has been definitely proved that the strength of concrete is determinable by one basic factor. This factor is the ratio of the volume of mixing water to the volume of cement, it being understood that the mixtures

when completed must be workable, such mixtures referring to the complete batch of aggregates. I have had in mind the foregoing determining factor controlling the strength of concrete in the development of the construction of my invention now to be set forth. In Figure 12 I have illustrated at one side of the frame 1 of the machine, the conveyor 16 carrying the buckets 17 much as heretofore set forth, the buckets 17 adapted to dump into the cement measuring hopper 38^a which corresponds with that previously described but is adapted to dump its charge of cement directly into the skip, or into the chute 62 that leads into the charging end of the mixer 2. The measuring hopper 38^a is equipped at its lower end with a discharge door 55^a normally held closed by means of a catch 85 capable of being tripped out of engagement with the door 85 by a trip arm 86.

The hopper 38^a is peculiarly mounted in that it is supported by links 87 which are pivoted at one end to the hopper body and pivotally connected at the opposite end as shown at 88 to the frame 1 of the machine. The links 87 connect the hopper for true vertical movement relatively to the frame 1, the supporting of the hopper being accomplished by mounting the same pivotally at 89 upon a weighing beam 90 which is adjustably fulcrumed as at 91 upon a vertical standard 92' carried by the frame 1. The weighing beam 90 supports at its end opposite the hopper 38 a water tank 92 adapted to receive water from a water main pipe 93 which includes the flexible section 94 and is in communication with the valve casing 95 at the top of the tank 92. In the casing 95 is a control valve 96 controlling the passage of water from the main 93 into the tank 92. This valve 96 is susceptible of operation by an actuating arm 97 attached to a rod 98 that leads to an arm 99 projecting from the outer end of the weighing beam or lever 90. A connecting link 100 is adjustably attached to the standard 92' and pivotally attached at 101 to the tank 92. For controlling the passing of water from the tank 92 down through the discharge pipe 102, I employ a wing valve 103 in a valve casing 104 just beneath the tank 92. Said valve casing 104 has an outlet extension that telescopes in the upper end of the water discharge pipe 102, the latter leading downwardly into the mixer drum 2 much as usually employed. Connected with the operating arm 106 of the valve 103 is an operating rod 107 that has its lower end formed with a trip arm 108 in the path of upward movement of the skip 4. The rod 107 has a shoulder or off-set 107' intermediate of its ends and a spring 109 normally tends to hold the rod 107 at its downward limit of movement maintaining the valve 103 closed. The batchmeter 5^a carried

by the frame 1 has an operating arm 110 connected to a rod 111 attached to a bell crank lever 112. The lever 112 carries a dog 113 adapted to gravitatingly engage beneath the off-set 107' of the rod 107.

In the operation of the just described construction of my invention, it is notable that when the measuring hopper 38^a is empty and the tank 92 is empty, the weight of the tank 10 will be sufficient to overbalance the hopper 38^a and maintain it in raised position. When the hopper 38^a is supplied with the batch of cement which is to be a part of the batch of aggregates charged into the mixer 2, the weight of the batch of cement in the hopper 38^a will overbalance and raise the water tank 92 incident to a rocking movement of the beam 90. As the tank 92 is moved upwards the rocking of the beam 90 causes a movement of the rod 98 and opens communication between the water main 93-94 and the tank 92. A supply of water is thus received in the tank 92 which bears a certain proportion to the weight of cement, such proportion being calculated so that at the time the water received by the tank 92 balances the weight of the cement in the hopper 38^a, the tank 92 will have moved downwards sufficiently to cut off the flow of water thereto. At such time, a measured quantity of water of a weight predeterminedly related to the weight of the cement 38 will be contained by the tank 92. The skip 4 is then raised in order to charge the aggregates therein, and the cement in the hopper 38^a into the mixer 2, along with the water from the tank 92. As the skip goes up, it travels the arm struck thereby 86 unlatches the catch 85 and permits the door 55^a of hopper 38^a to open and the cement from the hopper 1 flows therefrom to the chute 62 or mixer 2, as desired. Moreover, as the said skip rises, it strikes the arm 108 of the valve actuating rod 107, raises and opens the valve 103 and the water in the tank 92 which is now cut off from the water main 93 will feed through the pipe 102 into the mixing drum 2. The skip having charged the aggregates into the mixer is permitted to promptly return to its lowermost position and in fact it will have reached said position just about the time the water in the tank 92 has emptied into the mixer 2 so that the upward pressure on the rod 107 is relieved just as the tank 92 is empty or some time after said tank 92 is empty, this not being very material. Such relief of pressure on the rod 107 permits the valve 103 to close again. Of course, the tank 92 stays in its lower position until the conveyer 16 fills the hopper 38^a and thereby causes a fresh supply of water to enter the tank 92 through the elevation of the tank to its uppermost position by the weight of cement, the water continuing to flow until the beam 90 holds the

cement and water in counterbalanced relation as previously set forth.

In the use of my construction according to Figure 12, I throw the clutch of the conveyer 16 to start the movement of the conveyer during the downward movement of the skip instead of during its upward movement as called for by the mechanism of Figure 1.

75

Operation of batchmeter.

The batchmeter control acts as follows. As the skip 4 is raised as previously set forth and at a certain point in its movement the dog 113 engages beneath the off-set or shoulder 107'. Then on the down movement of the skip, the pressure of the latter on the arm 108 of the rod 107 is relieved and the rod returned to its lowermost position by the spring 109, thereby tripping the bell crank lever 112 by engagement with the dog 113 and setting the batchmeter 5^a into operation. The batchmeter 5^a is of the known type which predetermines or controls the mixing period during which the aggregates are mixed in the mixer 2. While the specific actuating connections for the batchmeter just set forth are not important because the operation may be caused by different kinds of parts, nevertheless the timing of the operation of the batchmeter is of high importance to the invention and is believed novel. It is essential under the rules of certain state engineering departments that all ingredients or materials which go to make up the batch of concrete, including the water, shall be in the mixer before the batchmeter is started into operation to control the mixing period. The operation of my invention therefore as to the action of the parts just mentioned conforms with the latest requirements in the above connection because the batchmeter will not start its control operation until the water has passed into the mixer 2, which will take place practically simultaneously with the charging of the solid aggregates into the mixer.

The type of water supply which I have shown in Figure 12 while possessing special importance from the view-point of its novel cooperation with the mixing machine and cement measuring instrumentalities may be modified, should it be desired to the extent that a conventional type of water supply could be used on my machine. Thus according to the construction in Figure 1, I may use the customary water tank arrangements now employed on concrete mixing machines, the discharge valve to be actuated, for instance, by the upward movement of the rod 33 which starts the conveyer 16 into action, and takes place on the rising movement of the skip 4 of Figure 1. I say this because I wish it to be understood that my invention while involving the water supply and cement

95

100

105

110

115

120

125

130

measuring features of Figure 12 is broader than this particular construction. Moreover, as to the Figure 12 construction, I do not wish to be confined to the weighing of 5 the water in proportioning it to the weight of the cement because I may connect up with the hopper 38 a volume varying device for a water receptacle, and thus measure the water in gallons instead of by 10 weight the effective action being much the same because a certain number of gallons of water will weigh a predetermined amount which will be proportioned to the weight of the cement to conform with the requirement 15 that the ratio of the volume of the mixing water to the volume of the cement shall be predetermined.

It is notable that I use any suitable power plant for the engine, preferably a gasoline 20 engine, beneath the hood A, Figure 1, and this power plant is adapted to operate all of the various parts of the machine together with the cement measuring means employed in conjunction therewith.

25 While I use an endless type conveyer 16 I do not wish to be confined thereto because I may employ a different conveyer device not having any endless belt or bucket features. So far as I am aware I am the first 30 to associate with a mixing machine, whether stationary or portable, a cement measuring device operating conjointly with the machine to supply measured quantities of cement thereto; also such a device which 35 counts the bags or cubic feet of cement and registers permanently the number of bags of cement handled in the machine; also a cement measuring device associated with water supply means in a mixing machine substantially as described.

40 It will be noted that the weight beam 90 is adapted to be adjustably mounted on the fulcrum axis 9 by the provision of a plurality of openings 90^a in said beam, also by 45 the provision of openings 100^a in the supporting link 100. The openings 90^a and 100^a permit of adjustment of the parts 90 and 100 in varying the relative proportions of the water handled by the tank 92 in relation 50 to the quantity of cement handled by the hopper 38^a.

The registers 25 and 25^a give complete information as to cement batch quantities and total batches and bags of cement handled. 55 The indications of disc 27 are carried by customary registering mechanism into register 25^b to total the bag count, which the batch count is given on register 25^a.

Having thus described my invention, what 60 I claim as new and desire to secure by Letters Patent of the United States, is:—

1. In combination, a concrete mixing machine, including aggregate charging means, a cement conveying device therefor, and 65 means to cause operation of the conveying

device from the charging means of the mixing machine, and stopping said device when it has conveyed a predetermined amount of material.

2. In combination, a concrete mixing machine, a cement measuring device therefor adapted to predetermine batch quantities of materials, comprising a cement conveyer and measuring hopper supplied thereby, and means to start and stop the action of 75 the measuring device from the mixing machine.

3. In combination, a concrete mixing machine, a cement conveyer for said machine, and automatic means controlling operation 80 of the conveyer to supply the machine with a predetermined quantity of cement as part of aggregates to be mixed in the machine, and cause the conveyer then to stop.

4. In combination, a concrete mixing machine, a charging device therefor, a cement conveyer for said machine, and means controlling operation of the conveyer to supply the machine with a predetermined quantity 85 of cement as part of aggregates to be 90 mixed in the machine, comprising the charging device of the mixing machine.

5. In combination, a concrete mixing machine, a charging device therefor, a cement conveyer for said machine, and means controlling operation of the conveyer to supply 95 the machine with a predetermined quantity of cement as part of aggregates to be mixed in the machine, comprising the charging device of the mixing machine, and a measuring 100 hopper arranged to receive the measured cement from the conveyer, and means to discontinue action of the conveyer when a predetermined amount of cement is fed to the hopper.

6. In combination, a concrete mixing machine, a charging device therefor, a cement conveyer for said machine, and means controlling operation of the conveyer to supply the machine with a predetermined quantity 110 of cement as part of aggregates to be mixed in the machine, comprising the charging device of the mixing machine, and a measuring hopper arranged to receive the measured cement from the conveyer, and means controlled by the charging means to discharge 115 the hopper of cement.

7. In combination, a concrete mixing machine, comprising a mixer, and a loading skip to charge the mixer with aggregates, and means on the machine for measuring cement to be supplied to the mixer, and means to control the cement measuring means from the loading skip, the measuring means including a conveyer on the machine, a measuring hopper to receive the cement from the conveyer, and means to discharge the hopper in supplying the cement to the mixer.

8. In combination, a concrete mixing machine, comprising a mixer, and a loading 120

- skip to charge the mixer with aggregates, and means on the machine for measuring cement to be supplied to the mixer, and means to control the cement measuring means from the loading skip, the measuring means including a conveyer on the machine, a measuring hopper to receive the cement from the conveyer, and automatic means to discharge the hopper in supplying the cement to the mixer and controlled from the loading skip. 5
9. In combination, a concrete mixing machine, comprising a mixer, a charging device therefor, an engine for operating the same, and a cement measuring device for supplying cement for mixture with other aggregates in the mixer, and operable by said engine, the measuring device including an endless conveyer for elevating the cement to supply the mixer, and a measuring hopper to receive the cement from the conveyer. 15
10. In combination, a concrete mixing machine, comprising a mixer, a charging device therefor, an engine for operating the same, and a cement measuring device for supplying cement for mixture with other aggregates in the mixer, and operable by said engine, the measuring device including an endless conveyer for elevating the cement to supply the mixer, and a measuring hopper to receive the cement from the conveyer, a discharge for the hopper, and means operated by the charging device for controlling the hopper discharge. 25
11. In combination, a concrete mixing machine, a cement conveyer for said machine, and means controlling operation of the conveyer to supply the machine with a predetermined quantity of cement as part of aggregates to be mixed in the machine, and water supply means for the mixing machine operably controlled by the conveyer. 40
12. In combination, a concrete mixing machine, a coating cement measuring device therefor, and a water measuring device operable to introduce water into the mixing machine simultaneously with the cement measuring device, and a common actuator for the two devices. 45
13. In combination, a concrete mixer, means for charging concrete aggregates into the mixer, a cement measuring device associated with the mixer, a water measuring device also associated with the mixer, and means for operating said two measuring devices from the charging means aforesaid, and controlling connections intermediate the cement measuring device and the water measuring device to coordinate the volume of mixing water supplied by the water measuring device with the volume of cement supplied by the cement measuring device. 55
14. In combination, a concrete mixing machine comprising a mixing drum and water and cement measuring devices mounted on said machine for supplying said drum with water and cement respectively, and automatic means for causing complete measured quantities of the cement and water from the water and cement measuring devices to be supplied to the mixing drum, at the same time. 70
15. In combination, a mixing machine comprising a mixing drum, a water measuring device, and a cement measuring device, means for supplying to the cement measuring device, and means for supplying water from the water measuring device to the mixing drum in variable volumetric proportions according to the weight of cement handled by the measuring device, and means for causing the cement from the measuring device to pass into the mixing drum. 75
16. In a concrete mixing machine, in combination, a mixing drum, a cement measuring device to supply said drum with the measured quantity of cement, a water measuring device for supplying said drum with water, and controlling means between the cement measuring device and the water measuring device to proportion the amount of water supplied to the drum by the water measuring device to the weight of the cement supplied from the cement measuring device. 80
17. In a concrete mixing machine, in combination, a mixing drum, a cement measuring device to supply said drum with the measured quantity of cement, a water measuring device for supplying said drum with water, and controlling means between the cement measuring device and the water measuring device to proportion the amount of water supplied to the drum by the water measuring device to the weight of the cement supplied from the cement measuring device; and means for varying the relative proportions of the cement and water supplied to the drum from the respective cement and water measuring devices. 90
18. In a concrete mixing machine, in combination, the mixing drum, a cement measuring hopper to supply cement thereto, a conveyer for supplying a measured quantity of cement to the measuring hopper, water supply means for the drum, and means common to the hopper and the water supply means for operating the cement and water supply means to cause the passing of the cement and water therefrom into the drum. 100
19. In a concrete mixing machine, in combination, the mixing drum, a cement measuring hopper to supply cement thereto, a conveyer for supplying a measured quantity of cement to the measuring hopper, water supply means for the drum, and means common to the hopper and the water supply means for controlling the passing of the cement and water therefrom into the drum, and a loading skip for charging supplied aggregate. 110
- 120
- 125
- 130

- gates into the drum with automatic operating means between the skip and cement and water supply instrumentalities for operating the latter.

5. 20. In a concrete mixing machine, in combination, a supporting frame, a mixing drum thereon, a cement conveyer adapted to receive cement to convey the same to a position for charging in the drum, and automatic control means for the conveyer for measuring the quantity of cement handled thereby and subsequently charged into the drum therefrom, and then discontinuing the operation of the conveyer.

10. 21. In a concrete mixing machine, in combination, a supporting frame, a mixing drum thereon, a cement conveyer adapted to receive cement to convey the same to a position for charging in the drum, and control means for the conveyer for measuring the quantity of cement handled thereby and subsequently charged into the drum therefrom, said conveyer inclining from a relatively low point on the frame to a higher point 25 of discharge, and a measuring hopper to receive the measured quantity of cement handled by the conveyer and supply the same to the drum.

25. 22. In a concrete mixing machine, in combination, a mixer, a conveyer adapted to supply cement to the mixer means for operating the conveyer and mixer, and control means for the conveyer for measuring the quantity of cement supplied thereby to the 30 mixer and then discontinuing the operation of the conveyer, and means for stopping and starting the conveyer automatically in relation to the operation of the mixer, by said control means.

40. 23. In a concrete mixing machine, in combination, a mixing drum, a bucket conveyer associated therewith and having buckets each adapted to receive the contents of a bag of cement, operating means for the 45 mixer and the conveyer adapted to operate the conveyer to carry the cement in the buckets to a position for charging into the drum, and means for controlling the conveyer to predetermine the number of buckets 50 of cement to be charged into the drum therefrom.

55. 24. In a concrete mixing machine, in combination, a mixing drum, a bucket conveyer associated therewith and having buckets each adapted to receive the contents of a bag of cement, operating means for the 60 mixer and the conveyer adapted to operate the conveyer to carry the cement in the buckets to a position for charging into the drum, and means for controlling the conveyer to predetermine the number of buckets 65 of cement to be charged into the drum therefrom, and registering means for registering the quantity of cement charged into the drum by the conveyer.

25. In a concrete mixing machine, in combination, a mixer, a cement measuring device for measuring a given number of specific quantities of cement therefor, means for supplying cement to the measuring device, means for supplying a batch consisting of said specific measured quantities of cement from the cement measuring device to the mixer, and means for registering the batches of cement thus supplied to the mixer from the cement measuring device, and thereby indicating the number of specific quantities supplied to the mixer. 70

26. In a concrete mixing machine, in combination, a mixer, a cement measuring device therefor, means for supplying cement to the measuring device, means for supplying measured quantities of cement from the cement measuring device to the mixer, and means for registering the batches of cement thus supplied to the mixer from the cement measuring device, and means for indicating the number of bags of cement in each batch of cement handled by the cement measuring device. 75

27. In a concrete mixing machine, in combination, a mixer, cement supply and measuring means for measuring a given number of specific quantities of cement therefor comprising instrumentalities for definitely measuring the amount of cement to be supplied to the mixer for each batch of other solid aggregates for making concrete, and recording means for counting the batches of cement handled by the measuring instrumentality aforesaid and thereby indicating the number of specific quantities supplied to the mixer. 80

28. In a mixing machine, in combination, a mixer, a water supply means for the mixer, a cement measuring device for the mixer, means for operating said water supply means, and cement measuring device to charge the mixer with water and cement, respectively therefrom, a batchmeter, and means to cause passage of water and cement from the respective water supply and cement measuring devices, and for operating the batchmeter after the water and cement are supplied to the mixer. 85

29. In a concrete mixing machine, a mixer, a cement measuring device, a loading skip, means for operating the measuring device to measure a batch of cement to be supplied to the mixer and controlling connections between said measuring device and the loading skip for causing operation and discontinuing operation of the measuring device. 90

30. In a concrete mixing machine, in combination, a mixer, and a cement measuring device, associated therewith, and means for operating the cement measuring device, said measuring device comprising a yieldably supported cement holding receptacle, and recording means for recording measured 95

100

105

110

115

120

125

130

quantities of cement handled by the measuring device and operable from the said receptacle only when the same is filled with cement.

5 31. In a concrete mixing machine, in combination, a mixer, a cement measuring device therefor comprising a conveyer, a cement feeding hopper for the conveyer and means operable by the conveyer for causing 10 cement in the hopper to be supplied to the conveyer automatically and incident to movement of the conveyer.

32. In a concrete mixing machine, in combination, a mixer, a cement measuring device therefor comprising a conveyer, a cement feeding hopper for the conveyer and means operable by the conveyer for causing cement in the hopper to be supplied to the conveyer automatically and incident to 20 movement of the conveyer, and a plural compartment supply hopper operable to progressively supply cement from any one of its hoppers to the feeding hopper aforesaid.

25 33. In a concrete mixing machine, in combination, a mixer, a cement measuring device therefor comprising a conveyer, a cement feeding hopper for the conveyer and means operable by the conveyer for causing 30 cement in the hopper to be supplied to the conveyer automatically and incident to movement of the conveyer, and a plural compartment supply hopper operable to progressively supply cement from any one 35 of its hoppers to the feeding hopper aforesaid, and automatic means for shifting the plural supply hopper to bring its compartments progressively to a position for supplying cement to the feeding hopper, and then 40 discharge the positioned compartment into said feeding hopper.

34. In a concrete mixing machine, a mixer, and means for charging concrete aggregates into the machine including a cement measuring device for measuring a given number 45 of specific quantities of cement, and a register for registering the measured quantities of cement handled by said device.

35. In a concrete mixing machine, in combination, a mixer and means for charging aggregates into the mixer for mixture therein, including a cement measuring device for measuring a given number of specific quantities of cement, said device embodying 55 counting means for counting the bag quantities of cement handled and included in a batch consisting of the said bag quantities.

36. In a concrete mixing machine, in combination, a mixer, and means for charging 60 aggregates into the mixer for mixture therein including a cement measuring device for measuring a given number of specific quantities of cement, said device embodying counting means for counting the bag quantities 65 of cement handled, which quantities

are included in batches handled by the mixer, and means for registering each measured quantity of cement charged into the mixer as a batch quantity substantially as described.

70 37. In combination, a concrete mixing machine comprising a mixer, and an aggregates batch charger, a water measuring device, a cement measuring device controlling the first measuring device, means to discharge the measuring devices into the mixer, and a batch meter operable after discharge of the water measuring device under control of the charger.

75 38. In combination, a concrete mixing machine comprising a mixer, and an aggregates batch charger, a water measuring device, a cement measuring device controlling the first measuring device, means to discharge the measuring devices into the mixer, 80 and means controlling replenishment of the measuring devices operable by the batch charger.

85 39. In combination, a concrete mixing machine comprising a mixer, and an aggregates batch charger, a water measuring device, a cement measuring device controlling the first measuring device, means to discharge the measuring devices into the mixer, 90 and means controlling replenishment and discharge, and a batchmeter operable after the discharge of said measuring devices, under the control of the charger.

95 40. In combination with a concrete mixing machine, a cement conveyer for feeding a certain required quantity of cement for mixing with other aggregates in the machine, power means to operate the mixing machine and conveyer, and automatic means to stop the conveyer when it has fed said 100 certain quantity of cement to said machine.

105 41. In combination with a concrete mixing machine, a cement conveyer for feeding a certain required quantity of cement for mixing with other aggregates in the machine, power means to operate the mixing machine and conveyer, and automatic means to stop the conveyer when it has fed said certain quantity of cement to said machine, and aggregate charging means for the mixing machine cooperative with the conveyer to start the same into operation.

110 42. In combination with a concrete mixing machine, a cement conveyer for feeding a certain required quantity of cement for 120 mixing with other aggregates in the machine, power means to operate the mixing machine and conveyer, and automatic means to stop the conveyer when it has fed said certain quantity of cement to said machine, and aggregate charging means for the mixing machine cooperative with the conveyer to start the same into operation, and means to register each certain quantity of cement 125 fed to the machine for mixing therein.

43. In combination with a concrete mixing machine, a cement conveyer for feeding a certain required quantity of cement for mixing with other aggregates in the machine, power means to operate the mixing machine and conveyer, and automatic means to stop the conveyer when it has fed said certain quantity of cement to said machine, and aggregate charging means for the mixing machine cooperative with the conveyer to start the same into operation, instrumentalities for supplying to the machine water of a quantity properly proportioned by the cement fed to the machine. 65
44. In combination with a concrete mixing machine, a cement conveyer for feeding a certain required quantity of cement for mixing with other aggregates in the machine, power means to operate the mixing machine and conveyer, and automatic means to stop the conveyer when it has fed said certain quantity of cement to said machine, other aggregate charging means for the machine, and water supply means operable by the cement handled by the conveyer so that water of a required quantity is controllably supplied to the machine. 70
45. In combination with a concrete mixing machine, a cement conveyer for feeding a certain required quantity of cement for mixing with other aggregates in the machine, power means to operate the mixing machine and conveyer, and automatic means to stop the conveyer when it has fed said certain quantity of cement to said machine, other aggregate charging means for the machine, and water supply means operable by the cement handled by the conveyer so that water of a required quantity is controllably supplied to the machine, with means between the said other aggregate charging means and the water and cement supply instrumentalities to cause these to enter the machine. 75
46. In combination with a concrete mixing machine, a cement conveyer for feeding a certain required quantity of cement for mixing with other aggregates in the machine, power means to operate the mixing machine and conveyer, and automatic means to stop the conveyer when it has fed said certain quantity of cement to said machine, other aggregate charging means for the machine, and water supply means operable by the cement handled by the conveyer so that water of a required quantity is controllably supplied to the machine and a batchmeter control for the machine suitable to operate after the cement and water have been supplied to the machine with the other aggregates by the operation of the other aggregate charging means. 80
47. In combination, a concrete mixing machine comprising a mixing drum, a convey- 85
- ing device for feeding a certain predetermined amount of cement for mixing in said drum, means for charging other aggregates into the drum, a water charging device for said drum mechanism whereby the cement, water and other aggregates are supplied to the drum substantially at the same times, and a batchmeter controlling the mixing operation of the drum and operable to be set for its controlling period incidental at the time of the charging of all of the cement, water and other aggregates into the drum. 90
48. In combination, a concrete mixing drum, aggregates charging means including a cement measuring and conveying device for conducting cement in a predetermined quantity to the drum for mixing therein, a water charging device for the drum cooperative with said cement measuring and conveying device so that the amount of water dispensed to the drum by said water charging device will be proportioned to the quantity of cement charged into the drum, and operating means for the cement measuring and conveying device for discontinuing its operation when a predetermined quantity of cement to be charged into the drum has been supplied. 95
49. In combination, a concrete mixing drum, aggregates charging means including a cement measuring and conveying device for conducting cement in a predetermined quantity to the drum for mixing therein, a water charging device for the drum cooperative with said cement measuring and conveying device so that the amount of water dispensed to the drum by said water charging device will be proportioned to the quantity of cement charged into the drum, and operating means for the cement measuring and conveying device for discontinuing its operation when a predetermined quantity of cement to be charged into the drum has been supplied, and a larger aggregates charging device arranged to cause the cement supplied by the cement conveying device, and the water proportioned in accordance therewith to pass into the drum for admixture with the larger aggregates. 100
50. In combination, a mixing machine, a cement elevating and conveying device associated therewith and having means to carry separate predetermined quantities of cement to a charging point for the mixing machine and means to operate the elevating and conveying device intermittently to bring a number of said predetermined quantities of cement to the charging point to form a batch for introduction into the machine, and means for registering each batch of cement thus prepared for charging into the machine and each individual quantity of those handled by the cement elevating and conveying device. 105

51. In combination, a mixing machine, a cement elevating and conveying device associated therewith and having means to carry separate predetermined quantities of cement to a charging point for the mixing machine and means to operate the elevating and conveying device intermittently to bring a number of said predetermined quantities of cement to the charging point to form a batch for introduction into the machine, and means for registering each batch of cement thus prepared for charging into the machine and each individual quantity of those handled by the cement elevating and conveying device, and means for supplying the cement elevating and conveying device consisting of a series of hoppers together with mechanism for shifting said hoppers in filled condition in relation to the conveying device to successively discharge the hoppers onto the latter.
52. In combination, a mixing machine, a cement hopper for holding a predetermined batch of cement to charge into the machine, means for feeding the cement in predetermined quantities to the hopper to cause bodily movement of the latter, and water measuring means comprising a tank and water inflow connections therefor operatively connected with the cement hopper so that the movement of the latter controls the supply of a measured quantity of water to the tank ready to be charged into the mixing machine.

In testimony whereof I affix my signature.

JOHN F. ROBB.
